louver slat elements 18 and 20. Each of these portions 32 is integral with respective aligned louver slat elements 18 and 20, thereby forming a respective continuous interconnecting portion which extends transversely through the strip 26.

As shown in FIG. 3 of the drawings, it will be seen that the locations 28 and 30 are disposed at the break line of the louver slat elements 18 and 20 and that each portion 32 of the strip 26 is integral with the respective ends 22 and 24 of the louver slat elements 18 and 20. It will be seen that opposite ends 34, of the louver slat elements 18 are blanked out from the break line location 28 coinciding with one side of the plate 12 while the end 22 adjacent to the end 24 of the louver slat element 20 is cut out to a location 36 which is spaced laterally of the louver break line locations 28 and 30 which align with each other.

When the louver slat elements 18 and 20 are blanked out of the plate 12 the portion of the forming die which punches the louver slat elements 18 and 20 outwardly to the desired angle also forms the strip 26 in the same direction whereby the portions 32 are formed laterally of one side of the plate 12 and into alignment with the louver slat elements 18 and 20. During the formation of the reinforcing portions 32 the strip 26 is stretched slightly in order to provide the offset disposition of the portions 32 which integrally interconnect the louver slat elements 18 and 20 to provide a continuous laterally offset reinforcing element for the louver plate 12. It will be seen from FIGS. 2 and 3 of the drawings that several rows of longitudinally spaced louver slat elements 18 and 20 may be arranged in parallel relationship to each other and that the portions 32 are all disposed laterally of one side of the plate 12 and transversely of the strip 26.

In operation the louver structures as shown in FIGS. 4 and 5 of the drawings may be stressed laterally in the direction of the arrows A by pads of excelsior or other foraminous material which are engaged with and retained by the louver slat elements 18 and 20 together with the other remaining surfaces at the inner or louver side of the plate 12.

It is contemplated that the present louver structure may be utilized for purposes other than evaporative cooler pads and that the louver slat elements 18 and 20 may be otherwise disposed. Regardless of the disposition of the louver slat elements 18 and 20 with respect to lateral loading of the plate the angular reinforcing portions 32 interconnecting the louver slat elements laterally of the plate will tend to resist bending stresses which may be created by loads imposed laterally of the plate from either side thereof.

In the modified louver structure as shown in FIGS. 6 to 10, inclusive, a louver plate is provided with a plurality of longitudinally spaced louver elements which are longitudinally staggered with relation to each other. As shown in FIG. 7 the louver slat elements 18 and 20 forming the upper row of longitudinally spaced louver slat elements are staggered with relation to the adjacent louver slat elements 18a and 20a. It will be seen that the middle portion of the louver slat element 18a is adjacent to the strip 26 of the plate 12 located between adjacent ends 22 and 24 of the louver slat elements 18 and 20, respectively. Between adjacent ends 22a and 24a of the louver slat elements 18a and 20a is a strip 26a of the plate 12 which is similar to the strip 26 as hereinbefore described. The strip 26a is located adjacent to a middle portion of a louver slat element 20. The reinforcing portion 32 of the strip 26 is similar to that hereinbefore described in connection with the structure disclosed in FIGS. 1 to 5 of the drawings. As shown in the enlarged view of the structure in FIG. 9 the strip portion 32 extends laterally of the plate 12 and is integral with the louver slat elements 18 and 20. This structure has the same stiffening effect as the leg of an angle iron or other angle member and is structurally similar in pro-

portion to its dimensional extension laterally of the plate 12.

It will be here noted that the staggered relation of the louver slat elements 18 and 18a permits the strips 26 and 26a to be staggered whereby stretching of these strips laterally to form the reinforcing portions 32 may be readily and easily accomplished. This staggered arrangement of the strips 26 and 26a may thus facilitate the fabrication of such louver structures of metal or other material which may difficult to stretch form.

In the modification of the present invention as shown in FIGS. 11, 12 and 13, a louver plate 40 is formed in a similar fashion to that of the louver plate 12 shown in FIGS. 6 and 7 of the drawings. The louver plate 40 as shown in FIG. 11 is in blank form wherein louver slat elements 18 and 20 are cut out but not angularly deflected into place.

A strip 42 similar to the strip 26 shown in FIG. 7 of the drawings is formed between adjacent ends of the louver elements 18 and 20 and this strip 42 is provided with a solid portion 44 and an expandable portion 46. The expandable portion 46 is provided with overlapping slits 48 similar to those found in conventional expanded metal.

As shown in FIGS. 12 and 13 the plate 40 is formed so that the louvers 18 and 20 are disposed at an angle to the plate and wherein the solid portion 44 of the strip 42 is disposed at an angle coinciding with the angle of the slat element 18 while the expandable portion 46 of the strip 42 is expanded into a structure similar to expanded metal.

The reason for the expandable structure 46 of the strip 42 is to permit the solid section 44 of the strip 42 to extend a considerable distance laterally of the plate 40 in alignment and integral with the louver slat elements 18 and 20. This extends the reinforcing structure of the solid portion 44 of the strip 42 and thereby greatly strengthens the plate laterally and between adjacent ends of the louver slat elements 18 and 20.

The expandable portion 46 of the strip 42 is capable of permitting extreme angular extension of the solid portion 44 of the strip 42 and permits the use of hard high tensile strength materials or permits the use of relatively thick materials as desired.

The expandable portion 46 of the strip 42 greatly alleviates the tendency of certain materials to crack when stressed to an extent comparable to that shown in FIG. 12 wherein the solid portion 44 of the strip 42 is very extensive.

The expandable portion 46 of the strip 42 thus provides an integral interconnected relationship between the plate 40 and the solid portion 44 of the strip 42 when the louver structure is formed as shown in FIG. 12 of the drawings.

It will be obvious to those skilled in the art that the expandable portion 46 of the strip 42 may be made in various ways as, for example, this expandable portion 46 may be formed by slitting or perforating as desired. Obviously the pattern of slits shown in FIG. 13 may be varied as desired to accomplish the intended results of considerable lateral extension of a solid portion 44 of the strip 42 in order to greatly increase the lateral reinforcing structure which integrally interconnects adjacent ends of the louver slat elements 18 and 20.

It will be obvious to those skilled in the art that various modifications of the present invention may be resorted to in a manner limited only by a just interpretation of the following claims.

I claim:

1. In a louver structure; a plate; first and second louver slat elements each integral with said plate and extending laterally of said plate at an angle thereto; said first and second louver slat elements being disposed in longitudinal alignment with each other and being spaced apart at their adjacent ends; a strip of said plate disposed between said adjacent ends of said first and second louver slat elements; a portion of said strip extending laterally of one side of said plate at an angle equal to that of said louver

slat elements, said portion being in alignment with and integral with said first and second louver slat elements.

2. In a louver structure; a plate; first and second louver slat elements each integral with said plate and extending laterally of said plate at an angle thereto; said first and second louver slat elements disposed in longitudinal alignment with each other and being spaced apart at their adjacent ends; a strip of said plate disposed between said adjacent ends of said first and second louver slat elements and a first portion of said strip extending transversely to said louver slat elements; a second portion of said strip extending laterally to one side of said plate at an angle equal to that of said louver slat elements, said second portion being in alignment with and integral with both of said first and second louver slat elements; said second portion forming a stiffener structure which interconnects said louver slat elements, one of said louver slat elements having an end opposite to its said adjacent end; said opposite end being cut away from said plate at a location coinciding with one side of said plate, said adjacent ends of said louver slat elements being cut away from said plate at a location spaced laterally of said one side of said plate.

3. In a louver structure; a plate; first and second louver slat elements each integral with said plate and extending laterally of said plate at an angle thereto; said first and second louver slat elements disposed in longitudinal alignment with each other and spaced apart at their adjacent ends; a strip of said plate being disposed between said adjacent ends of said first and second louver slat elements; a portion of said strip being disposed laterally of one side of said plate and integrally interconnecting said adjacent ends of said first and second louver slat elements.

4. In a louver structure; a plate; first and second louver slat elements each integral with said plate and extending laterally of said plate at an angle thereto; said first and second louver slat elements disposed in longitudinal alignment with each other and spaced apart at their adjacent ends; a strip of said plate disposed between said adjacent ends of said first and second louver slat elements; a portion of said strip being expanded to permit external lateral disposition thereof relative to a side of said plate; another portion of said strip being disposed laterally of one side of said plate and integrally interconnecting adjacent ends of said first and second louver slat elements.

5. In a louver structure; a plate; first and second louver slat elements each integral with said plate and extending laterally of said plate at an angle thereto; said first and second louver slat elements being disposed in longitudinal alignment with each other and being spaced apart at their adjacent ends; a strip of said plate disposed between said adjacent ends of said first and second louver elements; a first portion of said strip extending laterally of one side of said plate at an angle equal to that of said louver slat elements, said first portion being in alignment with and integral with said first and second louver elements which extend laterally of said plate; a second portion of said strip being slitted and expanded and integral with said first portion and said plate, said first and second portions extending laterally of the same side of said plate.

6. In a louver structure; a plate; first and second louver slat elements each integral with said plate and extending laterally of said plate at an angle thereto; said first and second louver slat elements being disposed in longitudinal alignment with each other and spaced apart at their adjacent ends; a strip of said plate being disposed between said adjacent ends of said first and second louver slat elements; a portion of said strip being disposed laterally of one side of said plate and integrally interconnecting said adjacent ends of said first and second louver slat elements, another portion of said strip being in stretched condition to permit lateral displacement thereof

from said plate, said strip portions being integral and effecting a bracing of said slat elements.

7. In a louver structure; a plate; first and second louver slat elements each integral with said plate and extending laterally of said plate at an angle thereto; said first and second louver slat elements being disposed in longitudinal alignment with each other and spaced apart at their adjacent ends; a strip of said plate disposed between said adjacent ends of said first and second louver slat elements and a first portion of said strip extending transversely to said louver slat elements; a second portion of said strip extending laterally to one side of said plate at an angle equal to that of said louver slat elements, said second portion being in alignment with and integral with both of said first and second louver slat elements; said second portion forming a stiffener structure which interconnects said louver slat elements, one of said louver slat elements having an end opposite to its said adjacent end; said opposite end being cut away from said plate at a location coinciding with one side of said plate, said adjacent ends of said louver slat elements being cut away from said plate at a location spaced laterally of said one side of said plate, the material of said first portion of said strip being stretched so as to be angularly related to said plate and to said second portion of said strip, and forming an integral connection therebetween.

8. In a louver structure; a plate; first and second louver slat elements each integral with said plate and extending laterally of said plate at an angle thereto; said first and second louver slat elements being disposed in longitudinal alignment with each other and being spaced apart at their adjacent ends; a strip of said plate disposed between said adjacent ends of said first and second louver slat elements; a portion of said strip extending laterally of one side of said plate at an angle equal to that of said louver slat elements, said portion being in alignment with and integral with said first and second louver slat elements, said strip having another portion integral with said first mentioned portion and extending therefrom to integral connection with said plate and being elongated so as to be angularly related to said first mentioned portion and to said plate.

9. In a louver structure; a plate; first and second louver slat elements each integral with said plate and extending laterally of said plate at an angle thereto; said first and second louver slat elements disposed in longitudinal alignment with each other and spaced apart at their adjacent ends; a strip of said plate disposed between said adjacent ends of said first and second louver slat elements and a first portion of said strip; a second portion of said strip extending laterally of one side of said plate at an angle equal to that of said louver slat elements, said second portion being in alignment with and integral with said first and second louver slat elements which extend laterally of said plate; said second laterally extending portion of said strip being integral with said louver slat elements laterally of said plate thereby forming a stiffener structure which interconnects said louver slat elements 60 through said second laterally extending portion of said strip; third and fourth louver slat elements similar in construction and parallel to said first and second louver slat elements; a second strip of said plate between said third and fourth louver slat elements and being similar to said first mentioned strip; said third louver slat element having a middle portion disposed adjacent said first strip whereby said third and fourth louver slat elements are longitudinally staggered relative to said first and second louver slat elements.

10. In a louver structure; a plate; first and second louver slat elements each integral with said plate and extending laterally of said plate at an angle thereto; said first and second louver slat elements disposed in longitudinal alignment with each other and spaced apart at their ad-

jacent ends; a strip of said plate being disposed between said adjacent ends of said first and second louver slat elements; a portion of said strip being disposed laterally of one side of said plate and integrally interconnecting said adjacent ends of said first and second louver slat elements, another portion of said strip being in stretched condition to permit lateral displacement thereof from said plate, said strip portions being integral and effecting a bracing of said slat elements, said other portion having an area provided with perforations and being stretched 10 at said area.
